UNITED STATES PATENT OFFICE.

ABRAHAM FRANK HOFFECKER, OF ELIZABETH, NEW JERSEY.

SEPARATOR.

No. 797,357.

Specification of Letters Patent.

Patented Aug. 15, 1905.

Application filed February 20, 1905. Serial No. 246,364.

To all whom it may concern:

Be it known that I, ABRAHAM FRANK HOFFECKER, a citizen of the United States, residing at Elizabeth, in the county of Union and State of New Jersey, have invented an Improvement in Separators, of which the following is a specification.

My invention relates to separators in which oil is removed from the water of condensation, and particularly to that type of this class of devices which is a component part of the power-generating apparatus of motor-vehicles in which steam is used as a motive power. Steam-power-generating systems for motor-vehicles, and particularly those employing that type of generator known as the "flash" or "semiflash" generator, generally include, together with the generator and engine or prime mover which is directly connected to the drive-wheels of the vehicle, a feed-pump and a condenser-pump, both of which are directly connected to the engine, a condenser, a tank, a separator in which the oil in the water of condensation from the condenser is to be separated before the same is led to the tank, and suitable connections from the tank to the generator by way of the feed-pump, from the generator to the engine, from the engine to the condenser, from the condenser to the separator by way of the condenser-pump, and from the separator back to the tank.

As commonly employed no provision whatsoever is made for regulating or controlling the pressure within the separator, and in practice I have found that under certain conditions this results in the non-performance by the separator of its specific function. Under ordinary working conditions when the engine is supplying power the condensed exhaust is properly taken care of by the condenser-pump and fed to the separator, where under these conditions the water of condensation is passed through a sieve or other device to the supply-tank, being thus freed from the lubricating-oil that it may have taken up while passing in the form of steam through the engine-cylinders. If, however, the engine is running idle, which from the direct-connected construction must be the case, for instance, when the machine is coasting and the pumps are also running due to their direct-constructed construction, the condenser-pump after having depleted the condenser of the water of condensation continues to operate and to create a considerable air-pressure in the separator sufficient, if the idle running

of the engine is continued long enough, to force the water with the oil remaining in the separator from the same to the tank, which causes all the troubles and inefficiencies in steam practice resulting from the mixture of oil with the feed-supply.

The object of my invention is to overcome the hereinbefore-described difficulty, and in carrying out the same I employ a separator provided with means for automatically preventing the liquid within said separator from dropping below a predetermined level, which means may be embodied in a relief-valve and suitable float by which the same is operated or otherwise, as may be found most expedient.

In the drawings, Figure 1 is a diagrammatic plan of a steam-generating apparatus for motor-vehicles, and Fig. 2 is a central longitudinal sectional elevation of a separator embodying the improvements comprising my invention.

a represents the engine, connected to the generator *b* by a steam-pipe 2.

c is the supply-tank, connected to the suction end of the feed-pump *d* by a pipe 3, and the discharge end of the feed-pump is connected to the generator by a pipe 4.

e is the condenser, connected to the engine-exhaust by a pipe 5, and *f* is the condenser-pump, connected to the condenser by a pipe 6 and to the separator *g* by a pipe 7, while the separator is connected to the tank *c* by a pipe 8.

Referring particularly to Fig. 2, the separator preferably comprises a casing or body portion 9, cylindrical or otherwise, as may be desired, and provided at its upper end with a cap 10, in which is a transverse opening 11. The opening 11 is screw-threaded, and I prefer to employ a short section of gas or other pipe 12, a portion of whose surface is also screw-threaded and adapted to be received in the opening 11 with a portion of the pipe 12 extending above the cap 10 and the lower end of the pipe extending slightly below the cap 10. Fitting closely within the pipe 12 and movable therein there is a rod 13, provided at its upper end with a pin 14. On the lower end of the rod 13 a float 15 is adjustably mounted, and above the float 15 there is a washer or valve 16, adapted when the float is raised to contact with the lower end of the pipe 12, and in the bottom of the separator there may be a suitable screen or sieve 17 conical or other shaped.

It will now be apparent that the float 15

may be set on the rod or stem 13, so that the valve 16 will be unseated at any liquid-level in the separator that is desired, thereby admitting the air and reducing the pressure which caused the height of the liquid to drop below the predetermined level.

In practice I have found that when the oil has accumulated to an extent sufficient to make it necessary to draw the same off the separator should be cleaned out, to accomplish which the cap 10 and parts associated therewith may be readily removed to gain access to the interior of the separator for this purpose.

I claim as my invention—

1. A separator for motor-vehicle steam-generating systems comprising a casing having an inlet thereto and an outlet therefrom, and means for maintaining the liquid-level within the separator at a predetermined height.

2. A separator for motor-vehicle steam-generating systems comprising a casing having an inlet thereto and an outlet therefrom, a screen in the bottom of said body, a cup fit-

ting within said body and means for maintaining the liquid within the separator at a predetermined level.

3. A separator for motor-vehicle steam-generating systems comprising a casing having an inlet thereto and an outlet therefrom, a cap, a valve-seat, a valve-stem, a valve, and means controlled by the liquid-level in said body for lowering and raising said valve.

4. A separator for motor-vehicle steam-generating systems comprising a casing having an inlet thereto and outlet therefrom, a cap, a pipe passing through the same, a valve-seat at the lower end of said pipe, a valve-stem, a valve in the same, and a float regulatably secured to said valve-stem for lowering and raising said valve with variations of the liquid-level in said body.

Signed by me this 16th day of February, 1905.

A. FRANK HOFFECKER.
